UNITED STATES PATENT OFFICE.

FRANKLYN W. WOOD, OF NEW YORK, N. Y.

METHOD OF MAKING PAPER-LINED RECEPTACLES.

1,366,621.

Specification of Letters Patent. Patented Jan. 25, 1921.

Original application filed May 14, 1920, Serial No. 381,229. Divided and this application filed June 4, 1920. Serial No. 386,481.

To all whom it may concern:

Be it known that I, FRANKLYN W. WOOD, a citizen of the United States, residing at New York city, in the county of New York 5 and State of New York, have invented certain new and useful Improvements in Methods of Making Paper-Lined Receptacles, of which the following is a specification.

This invention relates to the method of 10 making paper lined metal receptacles, the object of the present improvement being to provide a metal receptacle formed of a continuous spirally wound metal ribbon or strip with a lining of paper or other suitable material likewise formed of a continuous spirally wound ribbon or strip.

One of the objects of the present improvement is the provision of a cylindrical receptacle formed from a continuous spirally 20 wound strip of metal having the edges of the windings interlocked with a lining of paper likewise formed of a spirally wound strip of the same width as the metal strip and likewise having the edges of its windings interlocked and for this purpose the paper strip and the metal strip are both spirally wound at the same time so that the strip of paper also has its side edges interlocked with the interlocked edges of the 25 metal strips.

A further object of the invention is the method of lining a spirally wound metal receptacle with a spirally wound lining of a different material, the two being interlocked, by rolling the edges thereof together 35 during the winding thereof from continuous narrow strips of material.

In the drawings accompanying and forming a part of this specification, Figure 1 is 40 a side view of one form of the improved receptacle partly broken away; Fig. 2 is an enlarged detail view of a part of said receptacle; and Fig. 3 is a sectional view taken on line 3-3 Fig. 2.

Similar characters of reference indicate 45 corresponding parts in the several figures of the drawings.

This improved receptacle is made from a single narrow strip 2 of metal of thin gage 50 which by suitable machinery is spirally wound to any desired length and of any desired diameter. The edges of the continuous spiral strip 2 are rolled together and

interlocked in the manner shown by means of suitable rollers and dies. This is done 55 by hooking the edges together, (see Fig. 3).

It is desirable to provide this form of receptacle with a suitable lining, such for instance as a paper lining whereby the receptacle may be used for various purposes but 60 particularly as a container for food, and in order to do this I feed with the metal strip 2 a strip 4 of paper or other material, of the same width as the metal strip so that during the formation of the receptacle by 65 the spiral winding and the interlocking of the edges thereof, the edges of the paper strip 4 are likewise spirally wound and the edges thereof hooked or interlocked not only with each other but also with the edges of 70 the metal strip so that the paper lining is permanently fixed to the receptacle and the tearing or mutilation of the paper is largely prevented by reason of the fact that it is of narrow strip formation with its side edges 75 rigidly clamped.

In practice and according to one method of making this paper lined receptacle the paper strip may be pasted to the metal strip prior to the feeding of the strip to 80 the machine, or it may be fed with the metal strip by otherwise securing the two together or in any other desired way.

In practice should it be found necessary 85 for any reason to provide the interlocked joint with a suitable packing, such as a piece of cord 5, this can be readily done during the formation of the receptacle by merely feeding the same into the joint in the same way that the lining or paper is 90 fed.

The present application is a division of a contemporaneously pending application for 95 paper lined retainers, filed May 14, 1920, Serial No. 381,229.

I claim as my invention:

1. The method of making a lined receptacle which consists in spirally winding a narrow strip of metal and a narrow strip of lining together to form a receptacle of the 100 desired size, and connecting the edges of such strips during the formation of the receptacle.

2. The method of making a lined receptacle which consists in spirally winding a narrow strip of metal and a narrow strip of 105 lining together to form a receptacle of the

desired size, and interlocking the edges of such strips during the formation of the receptacle.

3. The method of making a lined receptacle which consists in spirally winding a narrow strip of metal and a narrow strip of lining together to form a receptacle of the desired size, and then rolling the edges of the strips together during the winding thereof, thereby to interlock them.

4. The method of making a lined receptacle which consists in spirally winding a continuous narrow strip of metal and a continuous narrow strip of paper together to form a receptacle of the desired size, and then connecting the edges of the strips together during the formation of the receptacle.

5. The method of making a lined receptacle which consists in spirally winding a continuous narrow strip of metal and a continuous narrow strip of paper together to form a receptacle of the desired size, and during such winding rolling the strips together thereby to interlock them.

6. The method of making a lined receptacle which consists in spirally winding a narrow strip of metal and a narrow strip of

lining together to form a receptacle of the desired size, connecting the edges of such strips during the formation of the receptacle, and during the connecting of the edges feeding thereto a packing.

7. The method of making a lined receptacle which consists in spirally winding a narrow strip of metal and a narrow strip of lining together to form a receptacle of the desired size, interlocking the edges of such strips during the formation of the receptacle, and feeding to such interlocked edges during the interlocking thereof a suitable packing.

8. The method of making a lined receptacle which consists in spirally winding a continuous narrow strip of metal and a continuous narrow strip of paper together to form a receptacle of the desired size and during such winding rolling the strips together thereby to interlock them, and during the rolling of the strips together to interlock them feeding to the interlocked edges a single packing.

Signed at New York, in the county and State of New York, this 28th day of May, 1920.

FRANKLYN W. WOOD.
